ELECTRICAL SWITCH

Charles Adin Fox, Oakland Village, Mo., assignor
to James R. Kearney Corporation, St. Louis,
Mo., a corporation of Missouri

Application November 3, 1944, Serial No. 561,648

5 Claims. (Cl. 200—48)

1

This invention relates generally to electrical switches, and more specifically to electrical switches of the disconnect type, the predominant object of the invention being to provide an electrical switch of this type which is of such improved construction and arrangement that a switch of extremely simple, light, and economical construction is provided which is capable of performing its intended function in a highly efficient manner, and is well able to withstand all of the mechanical abuses and bad weather conditions to which switches of this type are ordinarily subjected.

Fig. 1 is a side elevation of the improved electrical switch.

Fig. 2 is a front elevation of the switch illustrated in Fig. 1.

Fig. 3 is a top, plan view of the switch illustrated in Figs. 1 and 2.

Fig. 4 is an enlarged, horizontal section taken on line 4—4 of Fig. 1.

Fig. 5 is an enlarged, vertical section taken on line 5—5 of Fig. 1.

In the drawings, wherein is shown for purposes of illustration, merely, one embodiment of the invention, A designates the improved switch generally. The switch A comprises an insulator 1 while preferably, though not necessarily, is of the post type. The insulator 1 is illustrated as having fixed to it at its approximate longitudinal center a supporting bracket 2 which is adapted to facilitate attachment of the switch to a cross-arm, or other suitable supporting element (not shown).

Fixed to the insulator 1, at the upper end thereof, is the upper terminal 3 of the switch, and secured to said insulator, at its lower end, is the lower terminal 4 of the switch, said upper and lower terminals having connected to them through the instrumentality of suitable connectors 5 and 5' the incoming and outgoing lines L of the circuit with which the switch is associated. The upper terminal 3 comprises a block portion 3a from which is extended downwardly a semi-circular terminal portion 3b which embraces substantially one-half of the upper end portion of the insulator 1. The terminal 3 is secured to the insulator by a curved rod 6 which embraces and engages a portion of the insulator, as is shown in Fig. 1, end portions of said curved rod being extended through lugs 3c which are formed at opposite sides of the portion 3b of the terminal, and the outer, screwthreaded end portions of said curved rod having nuts mounted thereon which engage the forward faces of said lugs 3c and draw the curved rod into clamping engagement with

2

the insulator 1. Also, the upper terminal 3 includes an elongated eye 3d which extends upwardly from the block portion 3a of said terminal, and on a leg of which the connector 5 is mounted.

The lower terminal 4 includes a block portion 4a from which an elongated eye 4b is extended in a downward direction, the connector 5' being mounted on a leg of said elongated eye 4b. The lower terminal 4 is secured to the lower portion 10 of the insulator by a bolt 4', the head of said bolt being located outwardly of the block portion of the terminal and the shank of the bolt being extended through aligned apertures formed through said block portion of said terminal and through the wall of the insulator 1.

Fixed to the upper terminal 3 is the upper contact 6 of the switch A. The upper contact 6 is preferably formed from a single length of relatively heavy, resilient wire, or from suitable resilient rod material, the length of material from which the contact is formed being provided with a vertically disposed, inverted U-shaped loop 7 which is arranged in contact with the forward face of the block portion 3a of the upper terminal 25 3, as is shown to good advantage in Fig. 1. The upper contact 6 is secured to the upper terminal of the switch by a bolt 8 whose head engages the loop 7 of the upper contact, and whose screw threaded shank extends through said loop and is 30 screwthreadedly seated in a screwthreaded opening formed in the block portion 3a of the upper terminal.

Extended forwardly from the lower end of the loop 7 of the upper contact 6 is a pair of spaced contact portions 9 which are arranged in substantial parallelism, said parallel contact portions merging into convergent contact portions 10 which extend to the forward end of the contact (see Fig. 3). At their forward ends the convergent contact portions 10 are provided with outwardly bent portions 11 from which are extended rearwardly projected contact portions 12 that are spaced substantial distances outwardly from the convergent contact portions 10 to provide a pair 45 of opposed spaces 13. The contact portions 12 are provided with extensions 14 which are projected outwardly and rearwardly from the rear ends of said contact portions 12, and at the outer ends of these portions 14 knobs 15 are fixedly mounted thereon. It is important to note that the respective contact portions 12 are not arranged parallel with respect to the related contact portions 10, but instead, the space 13 between each contact portion 12 and its related contact portion 10 is 50 wider at the rear end of said space than at the forward end thereof. The importance of this ar-

arrangement will be hereinafter set forth. In order to maintain the spaced contact portions 9 of the upper contact 6 in their proper related positions bands 16 are arranged in embracing relation with respect to said contact portions. Also, a suitable cap 17 is applied to the outer end portion of the upper contact in embracing relation with respect to parts of the contact portions 10 and 12, to prevent undue spreading of the contact portions 12.

Associated with the lower terminal 4 is the movable blade 18 of the switch A, which is movable at its upper end into and out of electrical contact with respect to the upper contact 6 so as to establish and interrupt the electrical path through the switch. The blade 18 preferably is formed from a single length of relatively heavy, resilient wire, or suitable resilient rod material, the length of material from which the blade is formed being provided with a vertically disposed loop 19, of inverted U-shaped formation, which is arranged in contact with the forward face of the block portion 4a of the lower terminal 4. The blade 18 is secured to the lower terminal 4 by the bolt 4' which secures said lower terminal to the insulator, the head of said bolt engaging the loop 19 of said blade 18. Extended from the lower end of the loop 19 of the blade 18 is a pair of spaced contact portions 20 which, at their outer ends merge into the centers of a pair of spaced coiled portions 21 which are formed in the blade 18. These coiled portions serve to provide the blade of the switch with the resiliency required for the performance of its function, and extended from the outer portions of said coiled portions is a pair of convergent contact portions 22.

The blade 18 includes continuations 23 of the convergent contact portions 22 which are slightly convergent for a portion of their lengths (see Fig. 2) and at their outer ends the contact portions 23 are shaped to provide the blade 18 with a looped outer end portion 24. It is to be noted that space is maintained between the portions 23 of the blade throughout their lengths, and in order to maintain various related portions of the blade 18 in their proper positions suitable bands are employed, there being a band 25 which embraces parts of the blade portions 22, bands 26, 27, and 28 which embrace parts of the blade portions 23, and a band 29 which embraces the extreme outer end portions of said blade portions 23 at the end of the loop 24. In order to provide for good electrical connection between the lower terminal 4 and the blade 18 so that electrical energy passing from the blade to the lower terminal will not be compelled to pass through the coiled portions of the blade, a conductor 30 is employed. This conductor is clamped at one of its ends between the loop 19 of the blade 18 and the block portion 4a of the lower terminal by the bolt 4', and at its opposite end said conductor is soldered, or otherwise secured, to the band 25 of the blade.

When, in the use of the improved switch, it is desired to move the blade 18 of the switch from its open-switch position, as shown by dotted lines in Fig. 1, to its closed-switch position, as shown by full lines in Fig. 1, the finger of a suitable switch stick is introduced into the loop 24 at the outer end of said blade. The outer end portion of the switch blade is then moved upwardly and rearwardly to one or the opposite side of the upper contact, a portion of said switch blade located inwardly of the loop 24 thereof being moved rearwardly and inwardly around the appropriate upper contact 14 and knob 15, and be-

ing drawn forwardly into one or the other of the spaces 13 between the upper contact portions 10 and 12. When the outer end portion of the switch blade is moved upwardly and rearwardly as described, the coiled portions 21 of the blade are subjected to winding action which tensions said coiled portions and stores up force therein which tends to move the upper end of the switch blade outwardly and downwardly. As a result of tendency of the upper end portion of the switch blade to move outwardly and downwardly in response to force exerted by the tensioned coiled portions 21, the portion of the switch blade which is disposed in one of the wedge-shaped spaces 13 is forced deep therein. This causes the blade portions 23 to tightly engage the upper contact portions 10 and 12 at the opposite sides of said space to provide good electrical contact between said parts so that free flow of current from the upper contact 6 to the switch blade 18 will result. In this connection it is pointed out that because the portions 23 of the switch blade are spaced apart slightly, and because the upper contact portions 10 are likewise maintained in slight spaced relation, maintained spring-pressure contact is made between the resilient blade portions 23 and the resilient upper contact portions 10 and 12 when the switch blade is in the closed-switch position.

When it is desired to move the switch blade 30 from the closed-switch position to the open-switch position the loop 24 of the switch blade is engaged by a finger of a switch stick, and the upper end of the switch blade 18 is moved quickly and suddenly to the rear so as to break contact 35 between the switch blade and the upper contact in a manner to avoid arcing between those parts. The upper portion of the switch blade is then moved about the appropriate upper contact portion 14 and its knob 15 and the blade is lowered outwardly and downwardly to its lowered open-switch position.

In order to provide for the making of the best possible electrical contact between the upper contact 6 and the switch blade 18 of the switch A, auxiliary contact elements 31 and 32 may be applied respectively to the upper contact portions 10 and to the switch blade portions 23, as is shown to good advantage in Figs. 4 and 5. The auxiliary contacts 31 and 32 may be formed of silver, or other material which is characterized by being a very good conductor of electricity, said contacts being of substantially semicircular cross-sectional shape and being soldered, or otherwise secured, to the portions 10 of the upper contact and to the portions 23 of the switch blade in partial embracing relation with respect thereto. The auxiliary contacts 31 of the upper contact 6 face the spaces 13 of said upper contact between the portions 10 and 12 thereof, while the auxiliary contacts 32 of the switch blade are mounted on the switch blade portions 23 so as to face outwardly relative thereto. When the switch blade of a switch provided with the auxiliary contacts 31 and 32 is moved into contact engagement with the upper contact of the switch, electrical contact is made at one side of the switch blade by an auxiliary contact 31 associated with a portion 19 of the upper contact 6 and an auxiliary contact associated with one of the portions 23 of the switch blade. At the opposite side of the switch blade electrical contact is made by the auxiliary contact associated with the other of the switch blade portions 23 and a portion 12 of the upper contact of the switch.

I claim:

1. An electrical switch comprising an insulating support, spaced terminals supported by said insulating support, a contact electrically associated with one of said spaced terminals, said contact being formed from resilient wire-like material and said material of which said contact is formed being so bent and shaped as to provide the contact with a space between resilient portions of the contact which is closed at its front end by a portion of the contact located at the forward end of the contact and which is provided with an open rear end facing the rear of the contact, and a switch blade electrically associated with the other of said spaced terminals and movable into electrical contact with said contact, said switch blade being formed from resilient wire-like material and a portion of said switch blade being movable into said space of said contact to make contact with the resilient portions of said contact at opposite sides of said space, said portion of said switch blade which is movable into said space of said contact comprising a pair of spaced resilient parts of said switch blade.

2. An electrical switch comprising an insulating support, spaced terminals supported by said insulating support, a contact electrically associated with one of said spaced terminals, said contact being formed from resilient wire-like material and said material of which said contact is formed being so bent and shaped as to provide the contact with a tapered space between resilient portions of the contact which is closed at its front end by a portion of the contact located at the forward end of the contact and which is provided with an open rear end facing the rear of the contact, and a switch blade electrically associated with the other of said spaced terminals and movable into electrical contact with said contact, said switch blade being formed from resilient wire-like material and a portion of said switch blade being movable into said space of said contact to make contact with the resilient portions of said contact at opposite sides of said space, said portion of said switch blade which is movable into said space of said contact comprising a pair of spaced resilient parts of said switch blade.

3. An electrical switch comprising an insulating support, spaced terminals supported by said insulating support, a contact electrically associated with one of said spaced terminals, said contact being formed from resilient wire-like material and said material of which said contact is formed being so bent and shaped as to provide the contact with a space between resilient portions of the contact which is closed at its front end by a portion of the contact located at the forward end of the contact and which is provided with an open rear end facing the rear of the contact, and a switch blade electrically associated with the other of said spaced terminals and movable into electrical contact with said contact, said switch blade being formed from resilient wire-like material and a portion of said switch blade being movable into said space of said contact to make contact with the resilient portions of said contact at opposite sides of said space, said portion of said switch blade which is movable into said space of said contact comprising a pair of spaced resilient parts of said switch blade, and said switch blade being provided with a coiled portion which pro-

vides said switch blade with required increased resiliency.

4. An electrical switch comprising an insulating support, spaced terminals supported by said insulating support, a contact electrically associated with one of said spaced terminals, said contact being formed from resilient wire-like material and said material of which said contact is formed being so bent and shaped as to provide the contact with a space between resilient portions of the contact which is closed at its front end by a portion of the contact located at the forward end of the contact and which is provided with an open rear end facing the rear of the contact, and a switch blade electrically associated with the other of said spaced terminals and movable into electrical contact with said contact, said switch blade being formed from resilient wire-like material and a portion of said switch blade being movable into said space of said contact to make contact with the resilient portions of said contact at opposite sides of said space, said portion of said switch blade which is movable into said space of said contact comprising a pair of spaced resilient parts of said switch blade, said contact and said switch blade being provided with auxiliary contacts which move into contact engagement when the switch blade is moved to the closed-switch position in contact with said contact of the switch.

5. An electrical switch comprising an insulating support, spaced terminals supported by said insulating support, a contact electrically associated with one of said spaced terminals, said contact being formed from resilient wire-like material and said material of which said contact is formed being so bent and shaped as to provide the contact with a space between resilient portions of the contact which is closed at its front end by a portion of the contact located at the forward end of the contact and which is provided with an open rear end facing the rear of the contact, and a switch blade electrically associated with the other of said spaced terminals and movable into electrical contact with said contact, said switch blade being formed from resilient wire-like material and a portion of said switch blade being movable into said space of said contact to make contact with the resilient portions of said contact at opposite sides of said space, said portion of said switch blade which is movable into said space of said contact comprising a pair of spaced resilient parts of said switch blade, said contact and said switch blade being provided with auxiliary contacts which move into contact engagement when the switch blade is moved to the closed-switch position in contact with said contact of the switch.
